UNITED STATES PATENT OFFICE.

JAMES P. ELLIOTT, OF CHICAGO, ILLINOIS; MARY BRODERS ELLIOTT EXECUTRIX OF SAID JAMES P. ELLIOTT, DECEASED.

METHOD OF MAKING WATERPROOF AND ACIDPROOF RECEPTACLES.

Application filed October 28, 1920. Serial No. 420,280.

To all whom it may concern:

Be it known that I, JAMES P. ELLIOTT, a citizen of the United States, residing at Chicago, county of Cook, State of Illinois, 5 have invented a certain new and useful Improvement in Methods of Making Waterproof and Acidproof Receptacles, and declare the following to be a full, clear, and exact description of the same, such as will 10 enable others skilled in the art to which it pertains to make and use the same, reference being had to the accompanying drawings, which form a part of this specification.

There are many uses for receptacles which 15 shall be acidproof and waterproof, mechanically strong and durable, and not be too expensive, but, so far as I know, the problem has never been satisfactorily solved. One field that I have in mind is that of battery 20 boxes which are largely made of wood which is painted or otherwise coated with numerous coats of acid- and water-resistant material. Even if there were no other objection to boxes made in this way, there is 25 always the important objection that whenever the coating for the wood breaks down at one point the wood is exposed.

The object of the present invention is a simple and novel method for cheaply producing boxes or other receptacles in such a 30 way that they may be composed wholly of acid-resistant material and be given greater mechanical strength than that afforded by such material through the inclusion of reinforcing fibers; so that as long as the structure has not broken down sufficiently to 35 form a hole or crevice extending entirely through a wall thereof it will prevent acid contents thereof from reaching the exterior 40 and damaging surrounding things.

In carrying out my invention I build up a rudimentary receptacle by first forming a rudimentary bottom out of a plurality of layers or sheets of material made up of asphaltum, pitch, tar or other suitable material, then build up rudimentary side walls by forming a pile or stack of frame-like elements cut out of sheets of the same material used for the bottom wall, and then subject 45 the rudimentary receptacle, thus formed, to heavy pressure, and preferably to heat, so as to unite the various layers and compact the whole into a single homogeneous structure which will then consist substantially of 50 a single body of the acid-resistant material

having distributed throughout the same fibers to give toughness to the product.

The various features of novelty whereby my invention is characterized will herein-after be pointed out with particularity in 60 the claims; but, for a full understanding of my invention and of its objects and advantages, reference may be had to the following detailed description taken in connection with the accompanying drawing, wherein: 65

Figure 1 represents a rudimentary receptacle;

Fig. 2 is a transverse section through the rudimentary receptacle;

Fig. 3 is a section similar to Fig. 2 70 through the completed receptacle;

Fig. 4 is a diagrammatic view showing the rudimentary receptacle in a hydraulic press in which it is completed, the press being open; and

Fig. 5 is a view similar to Fig. 4, showing the press closed and the receptacle completed.

As heretofore explained, I first form a rudimentary receptacle out of sheets containing asphaltum, pitch, tar or other acid-resistant material and fibrous material. These sheets may be made in any suitable way, but I prefer to use sheets as they leave the paper-making apparatus in my prior 80 Patent No. 1,305,081, namely sheets made out of fibrous pulp with which there has been mixed a large proportion of comminuted asphaltum, pitch, tar or other suitable 85 substance; and, for the sake of brevity, I 90 shall confine the detailed description to a process utilizing sheets of this particular kind, although my invention is of course not limited to such sheets.

In carrying out the present invention I 95 make a stack of sheets containing the acid-resistant material and fibrous material, of sufficient mass to form the bottom of the receptacle and of a length and width approximating the length and width of such 100 bottom, such a stack being indicated at 1 in Figs. 1, 2 and 3 of the drawing. I then place upon the bottom-forming stack or rudimentary bottom a stack, 2, of frame-like pieces cut out of the same material as 105 that from which the rudimentary bottom is formed, so as to produce a rudimentary receptacle made up of a large number of layers resting loosely upon each other. This 110 rudimentary receptacle is then subjected to

heat and pressure in such a way that the bottom and side walls are compacted and densified, the acid-resistant material being melted or fused into a single mass or body 5 so as to produce the completed receptacle indicated at A in Figs. 3 and 5.

The transformation of the rudimentary receptacle into the completed product may be accomplished in various ways prefer- 10 ably, however, in a suitable hot press operated hydraulically or otherwise and, for the purpose of making my process clear, I have shown diagrammatically in Figs. 4 and 5 the elements of a suitable press to 15 accomplish my purpose. Referring to these two figures, 3 represents the bed of a press, this bed having a work-engaging face of the same size and shape as the surface of the bottom of the receptacle to be formed. 20 Surrounding the member 3 is a shell, 4, of a height somewhat greater than the height of the receptacle. Co-operating with the members 3 and 4 are two plunger elements, 25 5 and 6, the member 5 being in the form of a plunger whose cross sectional area is the same as the cross sectional area of the interior of the completed receptacle; while the member 6 is in the form of a shell surrounding the member 5 and of such cross 30 section as to permit it to enter the member 4 without leaving any undue amount of clearance between the exterior thereof and the inner surfaces of the member 4. The parts of the press are preferably heated in 35 any suitable way.

When the press is to be used, the parts thereof which are to come in contact with the work are preferably thoroughly coated with flux oil or any other suitable material 40 which will prevent the material of the receptacle from adhering to the press; then the rudimentary receptacle is placed upon the bed of the press and within the member 4 as shown and the press is closed as illus- 45 trated in Fig. 5. The press is closed under heavy pressure so that the material of the rudimentary receptacle is compacted and densified, preferably to such an extent that the specific gravity of the completed product 50 is approximately the same as the specific gravity of the asphaltum or pitch. The plunger, 5, is then raised and the shell, 4, lowered until clear of the inner and outer walls respectively of the receptacle, and the 55 member 6 is then raised, leaving the completed receptacle standing on the bed of the press.

It will be seen that the walls of the receptacle are subjected to pressure in all di- 60 rections so that complete uniformity of structure throughout the bottom and side walls may be obtained. Furthermore, if the heat is sufficient to make the asphaltum or pitch have the characteristics of a liquid or 65 semi-liquid, any inequalities in pressure

which might otherwise exist between differ- 70 ent points in the work would be equalized by the hydrostatic pressure transmitted through the material of the vessel itself. If the parts of the press are chambered for the admission of steam to heat the same, these same chambers may be employed for sub- 75 sequently cooling the work, by passing a cooling medium through the same, if this should be desired.

It will also be seen that if it be desired to make simply a tube or an endless wall, the process may be carried out just as described except that the layers or sheets, 1, adapted to form the bottom of the receptacle, will be 80 omitted.

A completed device made in accordance with my invention will have walls which, for all practical purposes, are solid bodies of a material which is waterproof, acid- 85 proof, and a non-conductor of electricity. The fibrous material contained in the structure and serving to give mechanical strength and toughness thereto will, in most instances, when dry, be an insulator of electricity but, 90 even though it should be more or less of a conductor, the fibers will be so thoroughly impregnated and coated with the insulating material that the insulating qualities of the structure as a whole will not be reduced 95 thereby. As heretofore stated, when the insulating coating of a wooden battery box breaks down at any point, the value of the box is greatly decreased; this being for the 100 reason that the moisture soaks into the wood and transforms the latter into a good conductor of electricity. This is of course only one of the uses to which my invention may be put, but the illustration serves, in a measure, to demonstrate some of the advantages 105 of my invention.

I claim:

1. The method of making a receptacle which consists in forming a pile of sheets composed of fibrous material and a material which is plastic at certain temperatures, some of the sheets being open at the center and the others extending across the opening to form the bottom of the receptacle, and then compressing the pile at one of the aforesaid temperatures to compact and densify the sheets and unite them into a unitary homogeneous body in which that portion forming the sides of the receptacle is shallower and thicker than in the original 115 pile.

2. The method of making a receptacle which consists in forming a pile of sheets composed of fibrous material and acid-re- 120 sistant material which is plastic and cem- entitious when heated, some of the sheets being in the forms of open frames to form the sides of the receptacle and a plurality of sheets at one end extending across the frame opening to form the bottom of the re- 130

ceptacle, and then subjecting the pile to heat and heavy pressure to compact and densify the sheets and unite them into a unitary homogeneous mass.

- 5 3. The method of making a receptacle which consists in forming a pile of sheets composed of fibrous material and a comminuted material which is plastic at certain temperatures, some of the sheets being open 10 at the center and some of the sheets at the bottom of the pile extending across the central open space of the other sheets, and then exerting a heavy downward pressure on all the upwardly directed faces of said pile 15 while holding the pile confined within a container engaging the inner and outer vertical walls and the under side of the bottom wall and while the pile is at one of the aforesaid temperatures.
- 20 4. The method of making a receptacle which consists in forming a pile of sheets composed of fibrous material and a large proportion of comminuted material which is plastic when heated, some of the sheets being 25 in the form of frames open at the center

and some of the sheets at the bottom of the pile extending across the open center of the remainder to form the bottom of the receptacle, and then subjecting the pile to heat and to heavy pressure on its upwardly directed faces while supporting the pile from below and also laterally from the interior and the exterior.

5. The method of making a receptacle which consists in forming a pile of sheets 30 composed of a material which is plastic at certain temperatures and fibers distributed throughout such material to bind the same together, some of said sheets being open at the center and the others extending across 35 the opening to form the bottom of the receptacle, and then compressing the pile at one of the aforesaid temperatures so as to fuse the aforesaid material into a single homogeneous mass and thus produce a monolithic 40 receptacle made out of such material having 45 fibers distributed throughout the same.

In testimony whereof, I sign this specification.

JAMES P. ELLIOTT.
